UNITED STATES PATENT OFFICE.

MOSES L. LORENTZ, OF NEW YORK, N. Y.

KEY-FASTENER.

SPECIFICATION forming part of Letters Patent No. 614,115, dated November 15, 1898.

Application filed August 23, 1898. Serial No. 689,320. (No model.)

To all whom it may concern:

Be it known that I, MOSES L. LORENTZ, a citizen of the United States of America, and a resident of the borough of Brooklyn, in the 5 city of New York, county of Kings, and State of New York, have invented a new and useful Improvement in Key-Fasteners, of which the following is a specification.

This invention relates to means for supplementing the ordinary locks or "dead-latches" 10 of doors, with reference to rendering the locked door more secure against intrusion or burglarious entry.

The present invention consists in a "safety-spring" of peculiar construction adapted 15 for use in connection with the ordinary door-key as a key-fastener.

A sheet of drawings accompanies this specification as part thereof.

20 Figure 1 of the drawings is a perspective view of the safety-spring detached. Fig. 2 is a fragmentary edge view of a locked door, showing the safety-spring in place; and Fig. 3 represents a horizontal section on the line 25 3, Fig. 2.

Like letters of reference indicate corresponding parts in the several figures.

The safety-spring S is of flat metal, preferably hard brass or steel, of suitable width, 30 having permanent bends, which form flanges a and b, at its respective extremities and a U-shaped bow c at one end, together with a bend d, substantially opposite said flange a, from which a straight stem e projects obliquely from the bow at a slight angle to a permanent bend f at its effective extremity, 35 said stem being doubled on itself, so as to locate said flange b close to the back of said bend d.

40 In Figs. 2 and 3 an ordinary door is represented at D, an ordinary door-lock at L, with its "dead-latch" bolt at g, a pair of keyhole plates or escutcheons at E, with keyholes at h, and the customary keyhole enlargement in 45 the door between said escutcheons at i, and the door-key at K, Fig. 2, with its ordinary bow (shown in edge view) at k.

The safety-spring S is fitted to the contracted lower or bit portion of the keyhole, with its 50 flange a interlocked with the escutcheon E at the inner or near side of the door within the near keyhole enlargement h, its stem e projecting into and preferably through the lock L, so as to prevent the insertion or operation

of a key or picklock from the other side of 55 the door, and the shoulder formed at b interlocking with the escutcheon on the other side of the keyhole.

The stem e, doubled on itself, as above described, renders the obstruction of the key-hole-passage more effective than a single stem, 60 without materially complicating the construction or operation of the safety-spring, which is also thus adapted to interlock with the escutcheon on both sides of the keyhole, so as 65 to effectively resist displacing pressure exerted against it through the keyhole-passage.

By simply giving the key the customary extra turn after the bolt is shot and then inserting the safety-spring the latter prevents unlocking the door by means of the key while 70 the spring is in place, the stem e crossing the path of the bit of the turned key, so as to prevent any unlocking movement.

The safety-spring is manipulated by grasping the bow c between finger and thumb and compressing the bow between the two until the flange a and the shoulder at b clear the interlocking escutcheon E, the spring being 75 inserted or withdrawn lengthwise.

The shape and relative proportions of the bow c may vary. The flange b and the doubling of the stem e may in some cases be omitted, and other like modifications will suggest 80 themselves to those skilled in the art.

Having thus described said improvement, I claim as my invention and desire to patent under this specification—

1. A key-fastener consisting of a safety-spring, of flat metal, having an outwardly-springing bow at one end provided with a flange to catch within the keyhole-passage for attaching the spring in place, and a stem at the other end of the spring to obstruct the 90 keyhole-passage and to interlock with the bit of the key.

2. A safety-spring, of flat metal, having an outwardly-springing bow provided with a flange to attach the spring in place within a 100 keyhole-passage, and a stem doubled upon itself to obstruct said passage and provided with a supplemental attaching-shoulder, substantially as hereinbefore specified.

MOSES L. LORENTZ.
